UNITED STATES PATENT OFFICE

172,734

RADIO CABINET

Lawrence H. Wilson, Detroit, Mich., assignor to
Admiral Corporation, Chicago, Ill., a corpora-
tion of Delaware

Application April 15, 1954, Serial No. 30,041

Term of patent 14 years

(Cl. D56—4)

To all whom it may concern:

Be it known that I, Lawrence H. Wilson, a citizen of the United States, residing at Detroit, in the county of Wayne, State of Michigan, have invented a new, original, and ornamental Design for a Radio Cabinet, of which the following is a specification, reference being had to the accompanying drawings, forming a part hereof.

Fig. 1 is a perspective view of a radio cabinet, showing my new design;

Fig. 2 is an elevational view of the left end of the cabinet;

Fig. 3 is an elevational view of the back thereof;

Fig. 4 is also an elevational view of the back, the antennae panel having been removed and shown in reversed position;

Fig. 5 is a sectional view taken on line 5—5 of Fig. 4;

Fig. 6 is a fragmentary sectional view taken on line 6—6 of Fig. 3; and

Fig. 7 is a fragmentary sectional view taken on line 7—7 of Fig. 3.

The dominant features of my design reside in that portion shown by full lines in the drawings.

I claim:

The ornamental design for a radio cabinet, as shown and described.
